DESIGN FOR A CLOCK CASE

Leo Ivan Bruce, Framingham, Mass., assignor to
Warren Telechron Company, a corporation of
Maine

Application January 22, 1942, Serial No. 105,372

Term of patent 7 years

To all whom it may concern:

Be it known that I, Leo Ivan Bruce, a citizen
of the United States, residing at Framingham, in
the county of Middlesex, State of Massachusetts,
have invented a new, original, and ornamental
Design for a Clock Case, of which the following
is a specification, reference being had to the ac-
companying drawing, forming a part thereof.

In the drawing, Fig. 1 is a front perspective
view of a clock case showing my new design and
Fig. 2 is a diagrammatic side view of the clock
case on a reduced scale.

I claim:

The ornamental design for a clock case, as
shown.

LEO IVAN BRUCE.
